ENGINE STARTING MECHANISM

John Gartner, New York, N. Y., assignor to
Eclipse Aviation Corporation, East Orange,
N. J., a corporation of New Jersey

Application October 16, 1935, Serial No. 45,333

10 Claims. (Cl. 74—7)

This invention relates to apparatus for starting internal combustion engines, such as those used in automobile power plants.

An object of the invention is to provide a simple, efficient and automatic apparatus of this character, preferably electrically motivated, and including a pinion adapted to be automatically engaged with gear teeth on the engine flywheel when a predetermined speed is attained, and thereafter disengaged by reverse torque action, and locked in the disengaged position.

Other objects of the invention will become apparent from inspection of the following specification when read with reference to the accompanying drawing wherein is illustrated the preferred embodiment of the invention. It is to be expressly understood, however, that the drawing is for the purpose of illustration only, and is not designed as a definition of the limits of the invention, reference being had to the appended claims for this purpose.

In the drawing:

Fig. 1 shows, in elevation, the preferred embodiment of the invention, and

Fig. 2 shows the same structure in longitudinal section, but with the pinion in the demeshed position.

Upon the extended armature shaft 1 of motor 2 there is preferably mounted a screw type of yielding drive, which, as shown, is substantially the commercial form of Eclipse-Bendix drive. This drive is characterized by a driving stud or head 7 secured to the driving shaft, a driving spring 9 connecting between said driving head and a corresponding stud 10 on the sleeve 16. This sleeve 16 is provided with a screw-threaded portion into which is screw-threaded the threaded extension 12 of a pinion 13 adapted to mesh with the teeth 14a of the engine fly wheel 14. The shaft 1 is journaled at its inner end in a bearing 3 toward which the pinion moves when shifted into mesh with the fly wheel.

As shown the sleeve 16 also includes a plurality of radial projections 17 having apertures 45 to receive pins 18 projecting from pawls 19 and constituting the means whereby said pawls may swing within the projections 17, the said pawls being normally held in the position indicated in the drawing by the action of compression springs 50 21 suitably retained and exerting a pressure holding the hook-ends 22 of the pawls in engagement with the flange 23 of the pinion. These pawls 19 are so designed that their centers of gravity are somewhat to the left of the bearing pins 18, so that upon rotation of the element

12 the centrifugal force established tends to swing the hook-ends 22 of the pawls away from the flange 23; but before the centrifugal force becomes sufficient to effect a complete release of the pinion, the rotating parts will have acquired considerable momentum, which momentum will be effective to insure positive torque transmission to the engine member 14 virtually instantaneously upon meshing of the pinion therewith. To increase the momentum, or "inertia" effect, the armature of motor 2 may be made heavier than it normally is.

When the engine starts on its own power the pinion is automatically demeshed by reason of its acceleration beyond the speed of the driving sleeve 16, and the resultant backward threading of the pinion; and in this demeshing movement the flange 23 rides under the sloping ends of the hooks 22 and is firmly caught thereby, the hooks having meanwhile returned to the position indicated in Fig. 1 by reason of the action of the springs 21, coupled with the fact that the driving sleeve 16 is now decelerated in response to the deenergization of the starting motor.

The friction exerted upon the forward end of 25 the pinion by the spring-pressed cone brake 31 insures a meshing movement of the pinion as soon as pawls 19 have released their hold on flange 23. Spring 32 is compressed during this meshing movement and facilitates demeshing 30 when the engine overruns.

What is claimed is:

1. An engine starting apparatus including a screw shaft having a pinion integral therewith and adapted to engage and crank a member of 35 the engine to be started, means for rotating said screw shaft and pinion, said rotating means including a threaded sleeve engaging said screw shaft for translating the rotary movement of said screw shaft into a longitudinal (engine engaging) movement, and means engageable with said pinion to render said translating means ineffective during low speed rotation of said sleeve.

2. An engine starting apparatus including a screw shaft having a pinion movable therewith 45 and adapted to engage and crank a member of the engine to be started, means for rotating said screw shaft and pinion, said rotating means including a threaded sleeve engaging said screw shaft for translating the rotary movement of said screw shaft into a longitudinal (engine engaging) movement, and means engageable with said pinion to render said translating means ineffective during low speed rotation of said sleeve, said last named means also acting to lock said pinion 55

in the non-meshing position after completion of the cranking action.

3. An engine starting apparatus including a shaft having a pinion integral therewith and adapted to engage and crank a member of the engine to be started, means for rotating said shaft and pinion, said rotating means including a sleeve engaging said shaft for translating the rotary movement of said shaft into a longitudinal (engine engaging) movement, and means engageable with said pinion to render said translating means ineffective during low speed rotation of said sleeve.

4. An engine starting apparatus including a shaft having a pinion movable therewith and adapted to engage and crank a member of the engine to be started, means for rotating said shaft and pinion, said rotating means including a sleeve engaging said shaft for translating the rotary movement of said shaft into a longitudinal (engine engaging) movement, and means engageable with said pinion to render said translating means ineffective during low speed rotation of said sleeve, said last named means also acting to lock said pinion in the non-meshing position after completion of the cranking action.

5. An engine starting apparatus including a driven member having a pinion integral therewith and adapted to engage and crank a member of the engine to be started, means for rotating said driven member and pinion, said rotating means including a driving member engaging said driven member for translating the rotary movement of said driven member into a longitudinal (engine engaging) movement, and means engageable with said pinion to render said translating means ineffective during low speed rotation of said driving member.

6. An engine starting apparatus including a driven member having a pinion movable therewith and adapted to engage and crank a member of the engine to be started, means for rotating said driven member and pinion, said rotating means including a driving member engaging said driven member for translating the rotary movement of said driven member into a longitudinal (engine engaging) movement, and means engageable with said pinion to render said translating means ineffective during low speed rotation of said driving member, said last named means also acting to lock said pinion in the non-meshing position after completion of the cranking action.

7. An engine starting apparatus including a

shaft having a cranking element integral therewith and adapted to engage and crank a member of the engine to be started, means for rotating said shaft and cranking element, said rotating means including a sleeve engaging said shaft for translating the rotary movement of said shaft into a longitudinal (engine engaging) movement, and means engageable with said cranking element to render said translating means ineffective during low speed rotation of said sleeve.

8. An engine starting apparatus including a shaft having a cranking element movable therewith and adapted to engage and crank a member of the engine to be started, means for rotating said shaft and cranking element, said rotating means including a sleeve engaging said shaft for translating the rotary movement of said shaft into a longitudinal (engine engaging) movement, and means engageable with said cranking element to render said translating means ineffective during low speed rotation of said sleeve, said last named means also acting to lock said cranking element in the non-meshing position after completion of the cranking action.

9. An engine starting apparatus including a driven member having a cranking element integral therewith and adapted to engage and crank a member of the engine to be started, means for rotating said driven member and cranking element, said rotating means including a driving member engaging said driven member for translating the rotary movement of said driven member into a longitudinal (engine engaging) movement, and means engageable with said cranking element to render said translating means ineffective during low speed rotation of said driving member.

10. An engine starting apparatus including a driven member having a cranking element movable therewith and adapted to engage and crank a member of the engine to be started, means for rotating said driven member and cranking element, said rotating means including a driving member engaging said driven member for translating the rotary movement of said driven member into a longitudinal (engine engaging) movement, and means engageable with said cranking element to render said translating means ineffective during low speed rotation of said driving member, said last named means also acting to lock said cranking element in the non-meshing position after completion of the cranking action.

JOHN GARTNER.
